Primary Examiner — Lauren R Calve(74) *Attorney, Agent, or Firm* — Jacob M. Ward; Ward Law Office LLC(57) **CLAIM**

The ornamental design for a closet organizer, as shown and described.

DESCRIPTION

FIG. 1 is a top perspective view of a closet organizer, wherein the break lines indicate indeterminate length; FIG. 2 is a bottom perspective view of the closet organizer shown in FIG. 1;

FIG. 3 is a top plan view thereof;

FIG. 4 is a bottom plan view thereof;

FIG. 5 is a front elevational view thereof; and,

FIG. 6 is a top perspective view of the closet organizer in an environment.

A right side elevational view is not shown because it is identical to the top plan view. A left side elevational view is not shown because it is identical to the top plan view. A rear elevational view is not shown because it is identical to the front elevational view. The claim is shown with a symbolic break in its length. The appearance of any portion of the article between the break lines forms no part of the claimed design. The ornamental design which is claimed is shown in solid lines in the drawings. The broken lines shown in the drawings are for the purpose of illustrating environment and form no part of the claimed design.
